CLAIM

The ornamental design for an internal seat pad of a sports garment, as shown and described.

DESCRIPTION

FIG. 1 is a top perspective view of an internal seat pad of a sports garment according to the new design;

FIG. 2 is a top plan view of thereof;

FIG. 3 is a bottom plan view thereof;

FIG. 4 is a left side elevational view thereof;

FIG. 5 is a right side elevational view thereof;

FIG. 6 is a front elevational view thereof; and,

FIG. 7 is a rear elevational view thereof.

It is understood that any portion of any figure shown in broken lines are for illustration of stitching, which is part of the claimed design.

1 Claim, 5 Drawing Sheets
